UNITED STATES PATENT OFFICE.

CHARLES SAMUEL FRANKLIN, OF LONDON, ENGLAND, ASSIGNOR TO MARCONI
WIRELESS TELEGRAPH COMPANY OF AMERICA, OF NEW YORK, N. Y., A CORP
PORATION OF NEW JERSEY.

AERIAL CONDUCTOR FOR WIRELESS TELEGRAPHY.

1,322,101.

Specification of Letters Patent. Patented Nov. 18, 1919.

Application filed March 4, 1916. Serial No. 82,042.

To all whom it may concern:

Be it known that I, CHARLES SAMUEL FRANKLIN, a subject of the King of Great Britain, residing at Marconi House, Strand, 5 London, England, have invented new and useful Improvements in or Connected with Aerial Conductors for Wireless Telegraphy, of which the following is a specification.

The object of this invention is to provide 10 an improved wireless aerial system which shall be particularly suitable for a receiving station used in conjunction with but separated from a transmitting station for duplex telegraphy.

15 It is known that an aerial system consisting of two frames at right angles to each other, and used in conjunction with a radiogoniometer, can receive best from any two opposite directions and eliminate signals 20 from any two opposite directions at right angles to the first.

According to this invention two similar 25 directional aerial systems, each consisting of two vertical frames at right angles to one another, are erected at equal distances from a transmitting station and at a distance apart which is a considerable fraction of the wave length it is desired to receive. The moving coil of the radiogoniometer connected 30 to each directional aerial system is connected to a pair of wires leading to the receiving apparatus which is preferably arranged mid-way between them. Condensers are introduced into the circuits comprising 35 the leading wires, the moving coils of the radiogoniometers, and the coils of the receiving apparatus in order to tune them to the desired wave.

The invention is illustrated by the accompanying 40 diagrams, in which Figure 1 shows a preferred relation between the receiving station and the transmitting station; Fig. 2 shows circuits which I may employ at a receiving station in accordance with one form 45 of my invention; Fig. 3 shows circuits which I may employ at a receiving station, in accordance with another form of my invention; and Fig. 4 shows circuits which I may employ at a transmitting station.

50 In Fig. 1, A, α are two aerial systems each consisting of two equal vertical frames at right angles to each other. They are situated at equal distances from an adjacent

transmitting station B which may have any type of transmitting aerial, and the distance 55 between them is a considerable fraction of the wave length it is desired to receive.

Presuming the station is arranged so that the direction of the received signals coincides with the line joining A, α , then the 60 maximum receiving power of the combination is obtained when A and α are placed at a distance equal to one half of the received wave length.

It is, however, generally more useful to 65 place them at a distance apart equal to one quarter of the received wave length.

Although it is advisable to arrange A, α in the line of the desired communication, considerable variation from this can be allowed.

In Fig. 2 C, c are two radiogoniometers the fixed coils of which are connected in the usual way to the aerial systems A, α respectively.

75 The moving coils D, d of the radiogoniometers are connected through tuning condensers E, e to coils F, f arranged to act upon a common coil G which is connected up to the receiving apparatus H through 80 the necessary tuning appliances.

As the directional systems are at equal 85 distances from the transmitting station B the oscillations produced in them by waves from B will be equal and in phase provided all the circuits are correctly tuned; then if the coils D, d are set at equal angles and the 90 couplings between F, G and f , G are equal and opposite, no effect will be produced in the receiving apparatus H.

90 With these adjustments, waves coming from any direction differing appreciably from the direction to or away from B will not produce opposing effects as the oscillations resulting in the two systems A, α will 95 not be in phase.

To eliminate signals from any desired direction other than that of B, it is only necessary to set the coils D, d respectively, to the angle at which the oscillations produced in 100 the two frame aerials of each system A, α , neutralize each other in their effects upon these coils.

The result is that this construction provides a receiving system which will not be 105 affected by waves coming from four dif-

ferent directions, two of which are fixed relatively to the station and two of which are controllable.

The invention can also be used in another way, *i.e.* supposing the radiogoniometer coils are set to eliminate waves from B and that A and α are a quarter wave length apart, then waves coming in the line joining A and α will produce in the circuits connected to

10 the radiogoniometers oscillations which are out of phase 90 degrees. If these circuits are mis-tuned in opposite senses so that the phases of the oscillations in the two circuits are advanced and retarded 45 degrees respectively, then waves coming from one direction will produce in the circuits oscillations which oppose, and waves coming from the other direction will produce oscillations which are in phase.

20 By coupling the radiogoniometer circuits, mis-tuned as above described, to two separate receivers H, h , Fig. 3, and arranging the couplings so that the oscillations in phase with each other in the two circuits operate as regards one receiver and add as regards the other, waves coming from one direction will actuate only the one receiver, and waves from the opposite direction will actuate only the other receiver.

30 It is therefore possible to receive from stations in opposite directions on the same wave-length without mutual interference and at the same time to transmit from an adjacent transmitting station.

35 A similar construction can be applied to a transmitting station. In this case suitable radiogoniometers capable of dealing with the energy are connected to two aerial systems similar to A, α , and the moving coils 40 of the radiogoniometers are supplied with high frequency alternating currents from an alternator or other source such as indicated at M in Fig. 4; then if the adjustments of the radiogoniometers are similar, 45 the system will not radiate waves in the directions at right angles to the line joining the two aerial systems nor in two opposite directions determined by the setting of the moving coils of the radiogoniometers.

50 What I claim is:

1. The combination at a wireless station of two similar aerials, each consisting of two vertical frames at right angles to one another, two radiogoniometers connected thereto and a common circuit inductively coupled to the moving coils of the two goniometers.

2. The combination at a wireless station of two similar aerials, each consisting of two vertical frames at right angles to one another, two radiogoniometers connected thereto, a common receiving circuit inductively coupled to the moving coils of the two goniometers and an adjacent transmitting station equidistant from the two aerials.

65 3. The combination at a wireless receiv-

ing station of two similar aerials situate at a distance apart equal to a quarter of the wave length of the waves to be received and each consisting of two vertical frames at right angles to one another, two radiogoniometers connected thereto and a common receiver inductively coupled to the moving coils of the two goniometers.

4. The combination at a wireless receiving station of two similar aerials situate at a distance apart equal to a quarter of the wave length of the waves to be received and each consisting of two vertical frames at right angles to one another, two radiogoniometers connected thereto, a common receiving circuit inductively coupled to the moving coils of the two goniometers and an adjacent transmitting station equidistant from the two aerials.

5. The combination at a wireless station of two similar directive aerials spaced apart, said aerials each having a plurality of aerial sections which form parts of distinct circuits, and a common circuit inductively coupled to said aerials.

6. The combination at a wireless station of two similar directive aerials situate at a distance apart equal to a fraction of the wave length of the waves to be received, each of said aerials having a plurality of aerial sections which form parts of distinct circuits, and a common circuit inductively coupled to said aerials.

7. The combination at a wireless station of two similar directive aerials situate at a distance apart equal to a quarter of the wave length of the waves to be received, and a common circuit inductively coupled thereto.

8. The combination at a receiving station of two similar directive aerials situate a distance apart equal to a fraction of the wave length of the waves to be received, each of said aerials having a plurality of aerial sections which form parts of distinct circuits, a common receiver inductively coupled to said aerials, and an adjacent transmitting station equidistant from the two aerials.

9. The combination at a wireless station of two similar aerials, each consisting of two vertical frames at right angles to one another, two radiogoniometers connected thereto, and common receiving means inductively coupled to the moving coils of the two goniometers.

10. The combination at a receiving station of two similar aerials each consisting of two vertical frames at right angles to one another, two radiogoniometers connected thereto, receiving means inductively connected to the moving coils of the two goniometers, and an adjacent transmitting station equidistant from the two aerials.

11. The combination at a wireless receiving station of two similar aerials situate at a

- distance apart equal to a fraction of the wave length of the waves to be received, and each consisting of two vertical frames at right angles to one another, two radiogoniometers connected thereto, and common receiving means inductively coupled to the moving coils of the two goniometers.
12. The combination at a wireless receiving station of two similar aerials situate at 10 a distance apart equal to a quarter of the wave length of the waves to be received, and each consisting of two vertical frames at right angles to one another, two radiogoniometers connected thereto, receiving 15 means inductively coupled to the moving coils of the two goniometers, and an adjacent transmitting station equidistant from the two aerials.
13. The combination at a wireless station 20 of two similar directive aerial systems whose centers are spaced apart, each of said said aerial systems comprising a plurality of horizontally extending aerial sections arranged approximately parallel to aerial sec- 25 tions of the other aerial system, and a common circuit inductively coupled to said aerial systems.
14. The combination at a wireless station of two similar directive aerial systems whose centers are situated at a distance apart 30 equal to a fraction of the wave length of the waves to be received, each of said aerial systems comprising a plurality of horizontally extending aerial sections arranged approximately parallel to aerial sections of the other 35 aerial system, and a common circuit inductively coupled to said aerial systems.
15. The combination at a receiving station of two similar directive aerial systems whose centers are situated a distance apart equal to 40 a fraction of the wave length of the waves to be received, each of said aerial systems comprising a plurality of horizontally extending aerial sections arranged approximately parallel to aerial sections of the other aerial 45 system, a common receiver inductively coupled to said aerial systems, and an adjacent transmitting station equidistant from the two aerials.

CHARLES SAMUEL FRANKLIN.
